CASTING APPARATUS

Albert H. Jung, Flushing, N. Y., assignor to United American Metals Corporation, Brooklyn, N. Y., a corporation of New York

Application July 21, 1938, Serial No. 220,534

3 Claims. (Cl. 22—143)

This invention relates to casting apparatus and more particularly to an ingot mold of such shape and characteristics as to facilitate the casting of ingots therein, the removal of the ingots therefrom, and to afford protection to the molds when stacked.

Prior to my invention molds have been designed which were adapted to cast slotted-eared ingots of a type suitable for use with an automatic feeder, but such molds have been conventional in structure, being simply negatives of the ingot to be cast or molds with but slight modification from the negative of the ingot. Such prior molds, while they have been used to effect the casting of desired ingots, have been relatively awkward to handle and work with, and when highly designed, they have been relatively delicate and great care must be exercised in their arrangement and storage.

It is an object of my invention to provide an ingot mold of characteristics which facilitate the casting of ingots therein.

It is a further object of my invention to provide an ingot mold of characteristics which facilitate the casting of ingots therein and further permit of particular stacking in a manner to prevent injury.

Other objects and the nature and advantages of the invention will be apparent from the following description taken in conjunction with the accompanying drawing, wherein:

Fig. 1 is a view in perspective of a tilttable water cooled double mold in accordance with my invention;

Fig. 2 is a fragmentary top plan view of the embodiment illustrated in Fig. 1;

Fig. 3 is a fragmentary sectional view of the embodiment illustrated in Fig. 1; and,

Fig. 4 is a view similar to Fig. 3 of a modified form in accordance with my invention.

Referring to Figs. 1, 2 and 3, a mold 10 may comprise a pair of similar sections 11 and 12 each having cavities comprising relatively deep body portions 13 and relatively shallow end portions 14 wherein are situated cores 15 and webs 16. The webs 16 may comprise a lower relatively thick portion 17 and an upper relatively thin portion 18. The cores may have their upper surfaces formed with sloped portions 19 as illustrated. At the outer side of each mold section, notches 20 may be formed in the side walls of the main body portion 13. The walls of the mold 10 are hollow and may comprise a chamber 21 through which cooling water is adapted to be passed to reduce the time of solidification of the

ingot. Water may enter the chamber 21 through the conduit 22 which may also act as a stub shaft when supported in a suitable bearing, not shown, to permit the mold 10 to be rocked or tilted after the solidification of the ingot and it is desired to remove the cast ingots. The cooling water having passed completely around the inner wall 23 of the mold may leave the mold 10 through a conduit, not shown, at the opposite end thereof.

The outer walls 24 at the ends of the lower side of the mold 10 may be cupped to accommodate the cores 15 when the molds are stacked, one above the other, for storage or for any other purpose such as for shipment, for example. The cores 15 extend above the upper portion of the side walls 25 of the mold 10, whereas the upper portions 18 of the webs 16 extend somewhat below the upper portion of the side walls 25 of the mold 10. The notches 20 extend slightly below the top of the upper portions 18 of the webs 16.

With this arrangement after the molten metal has been cast into the mold 10 and the cooling water between the walls 23 and 24 of the mold 10 has served to solidify the molten metal, the mold 10 may be tilted to facilitate the removal of the cast ingots. When the mold 10 has been tilted to such an extent that the ingots have moved to a position in spaced relation to the bottom of the molds 11 and 12, the ends of the ingots will rise up, to some extent, on the high cores 15 permitting the operator to grasp the slots formed in the ends of the ingots by the web 16, for the webs are not as high as the cores, see Fig. 3. When the ingots are of such a size, say from thirty to sixty inches in length, the operator may grasp the slotted end portions of the ingots with gloved hands or some special tool or tools and easily remove the same for

stacking or other arrangement. In practice, the angle of tipping is soon learned which will cause separation of the ingots from the mold to an extent which will readily permit the hand or fingers of the operator to grip the exposed slotted end portions of the mold directly above the web portions 16 and facilitate the handling of the ingots. Further, the ingenious relation of the slot to the core and web will insure a true slotted ingot which is not "finned" over at the slot and yet permit the operation described.

Slotted-eared ingots cast in the mold illustrated in Figs. 1, 2 and 3, in accordance with my invention, lend themselves readily for mounting on automatic ingot feeders such as the "Mar-gach" feeder which may comprise an endless

chain having secured thereto a series of hooks on each of which one end of each ingot is to be threaded. As the endless chain is placed in motion, one ingot at a time is fed into the molten metal bath and when the ingot has been lowered to a point at which the lower end of the upper slot is even with the level of the molten material in the molten bath, the remainder or unmelted portion of the ingot will slip off by virtue of the location of the center of gravity of each side of the slotted-ear whereby the attention of the operator is unnecessary in the complete removal of the ingot from the feederhook and be fed into the bath. The endless chain in its motion will then feed another ingot to the molten bath and the cycle will be repeated.

Ingots of this type are by their nature more fragile at the slotted-eared portion than at the main body portion, and in shipment frequent breakage occurs at the slotted-eared portion. As ingots with broken slotted-eared portions cannot be used in connection with the automatic feeder, the broken pieces must be shipped back to the place of casting for recasting. This makes for great inconvenience, increases the total shipping and handling costs and may be obviated to a great extent by forming each end of the ingot with a slotted ear, whereby if one end is injured, the usefulness of the ingot is not entirely impaired, for the other whole end may be utilized for threading on the automatic feeder. Furthermore, the particular configuration of the cores, webs, and their association with molds in accordance with my invention further facilitate handling of ingots cast within the mold. The tall cores act to relatively securely hold the ingots even though the molds have been tilted in a manner to cause the ingots to move up on the cores and away from the bottoms of the molds. Further, the webs which are lower than the cores permit the insertion of the fingers of the operator or the two hands of the operator in a manner whereby the said operator may readily lift the ingot from the mold and stack same for storage or for shipment.

The embodiment illustrated in Fig. 4 is similar to that depicted in Figs. 1, 2 and 3 with the exception that both the core 35 and the web 36 do not rise to the full height of the side walls 37 of the cavity 38 of the mold 39. The slot 40 formed in the side walls 37 extends somewhat lower than the top portions of the core 35 and the web 36 to insure a true slot in each end of the ingots caused therein and to prevent a "finned" over end portion. With this arrangement, the bottom wall 41 may be perfectly flat and yet permit the molds 39 to be stacked, one above the other, without injury to the cores 35 or web 36 as the walls 37 extend above the same.

It will be obvious to those skilled in the art that various changes may be made in this device without departing from the spirit of the invention and therefore the invention is not limited to what is shown in the drawing and described in the specification but only as indicated in the appended claims.

I claim:

1. A slotted eared metal ingot mold of the kind suitable for use in the casting of ingots for association with automatic type metal feeders such as the "Margach" feeder, said mold having side, end and bottom walls forming a cavity, said mold having an elongated body portion and an end portion and an end wall, an upstanding relatively thick strong core formed integral with the bottom wall of said end portion, an upstanding web comprising a relatively thin fragile portion formed integral with the core, bottom wall and end wall of the end portion, the top of said web and the top of said core being definitely at variance with each other in that the top of the core is higher than the top of said web, whereby when the mold is tilted an ingot cast therein may ride up on the core and permit the insertion of a tool or the gloved fingers of the operator into the slot formed by the web and the removal of the ingot without dropping thereof is greatly facilitated.

2. A slotted eared metal ingot mold of the kind suitable for use in the casting of ingots for association with automatic type metal feeders such as the "Margach" feeder, said mold having side, end and bottom walls forming a cavity, said mold having an elongated body portion and an end portion having a bottom wall and an end wall, an upstanding relatively thick strong core formed integral with the bottom wall of said end portion, an upstanding web comprising a relatively thin fragile portion formed integral with the core, bottom wall, and end wall of the end portion and extending from said bottom wall to a height lower than the top of said side walls, whereby a plurality of molds may be stacked without injury to said relatively fragile webs and whereby when each mold is tilted an ingot cast therein may ride up on the side wall and permit the insertion of a tool or the gloved fingers of the operator into the slot formed by the web and the removal of the ingot without dropping thereof is greatly facilitated.

3. A slotted ear metal ingot mold of the kind suitable for use in the casting of ingots for association with automatic type metal feeders such as the "Margach" feeder, said mold having side, end, and bottom walls forming a cavity, said mold being elongated, an upstanding relatively thick strong core formed integral with the bottom wall at an end thereof and extending to a height above the said side walls, an upstanding web comprising a relatively thin, fragile portion formed integral with the core, bottom wall and adjacent end wall and extending from the said bottom wall to a height lower than the top of said side walls, the top of said web and the top of said core being definitely at variance with each other, whereby when the mold is tilted an ingot cast therein may ride up on the core and permit the insertion of a tool or the gloved fingers of the operator into the slot formed by the web and the removal of the ingot without dropping thereof is greatly facilitated.

ALBERT H. JUNG.
